FIREARM

Carl H. Benson, New Haven, Conn., assignor to O. F. Mossberg & Sons, Inc., North Haven, Conn., a corporation of Connecticut

Filed Apr. 28, 1964, Ser. No. 79,726

Term of patent 14 years

(Cl. D30—1)

Fig. 1

Fig. 2

Fig. 3

FIG. 1 is a side view of a firearm showing my new design, portions thereof being broken away for convenience of illustration:

FIG. 2 is a perspective view thereof;

FIG. 3 is a top plan view of the same; and

FIG. 4 is a top perspective view of the complete firearm shown in FIGS. 1 to 3, inclusive, but taken from the other side of FIG. 2.

The dominant features of the design reside in the portions shown in full lines on the drawing. In FIGS. 2 and 3 portions of the gun are shown broken away for convenience of illustration.

I claim:

The ornamental design for a firearm, substantially as shown and described.
